2 SHEETS—SHEET 2.

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,389,494.

Specification of Letters Patent. Patented Aug. 30, 1921.

Application filed December 27, 1920. Serial No. 433,371.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 This invention relates to improvements in railway signal torpedoes, and pertains to a novel way of securing the rail-engaging member to the torpedo case.

The primary object of my invention is to 15 connect the rail-engaging member to a torpedo case by a string which may be constructed of either fiber or a fine string of pliable wire wrapped around the rail-engaging member at the edge of the case and across 20 the top of the torpedo case.

A further object of my improvement is to hold the string of fiber or wire in its position on the case and rail-engaging member by a 25 band or ring which embraces the edge of the case and confines the string at that point between the ring and the case.

Further objects of my present improvement will appear from the following description.

30 In the accompanying drawings:—

Figure 1 is a perspective view of the torpedo having a spring rail-engaging member, showing my improved connecting means applied thereto.

35 Fig. 2 is an inverted plan view of Fig. 1, the ends of the spring being broken away.

Fig. 3 is an edge view of Fig. 1.

Fig. 4 is an enlarged central vertical section of Fig. 1.

40 Fig. 5 is a top perspective view of a torpedo carrying a lead attaching strap showing my improved connecting means applied thereto.

Fig. 6 is an inverted perspective view of 45 Fig. 1.

Fig. 7 is a top perspective view of the torpedo, shown in Fig. 5 with the embracing ring shown in separated relation.

Fig. 8 is an enlarged central vertical section of Fig. 5.

Fig. 9 is a bottom plan view of Fig. 5.

Referring now to the drawings in which the same reference numerals apply to like parts, 1 is a torpedo case and 2 a spring rail-attaching member, which is applied to the

under side of the case 1. The shape of the spring 2 forms no part of my present improvement, as the spring may be of any suitable shape without affecting my present improved manner of securing it to the case. 60

In carrying out my present improvement, I provide a string 3, which may be formed of fiber or fine pliable wire, such, for instance, as copper or annealed steel or iron. This string 3 is passed under the rail-attaching member 2 and across the top of the case 1, making an approximate X-shape arrangement 4 at the top of the case, as clearly shown in Figs. 1, 5 and 7. The string 3 also passes down the edge of the case at four 70 points 5, and then either under or around the spring 2, or both, the wrapping being tied. An embracing and holding band 6 is then forced over the edge of the torpedo case and clamps the downwardly extending portions 75 5 of the string between the ring and the edge of the case. This string will be passed under or around the rail-attaching member and across the top of the case, preferably several times. The ends of the string may 80 be tied together into a suitable knot 7, or fastened in any other desired manner.

The embracing ring or band 6 fits the edge of the case tight and, therefore, tightly 85 clamps the downwardly extending parts 5 of the string and the case and also serves to tighten and hold tight the string. In this construction nothing in addition to the ring is necessary to hold the string in its wrapped positions. In fact, the ends of the string 90 may be cut off after the ring has been placed in position, owing to the fact that it is tightly clamped between the ring and the case, as stated.

It will be observed from this arrangement 95 of the string that it does not extend across the bottom of the torpedo case, nor across the spring intermediate the edges of the torpedo case.

The construction and arrangement of the 100 securing string is the same as in Figs. 5 to 9, as shown in Figs. to 1 to 4, with the exception that Figs. 5 to 9 show a lead rail-attaching strap instead of a spring attaching strap, or member. The description and reference 105 characters of Figs. 1 to 4, therefore apply also to Figs. 5 to 9, inclusive.

After the rail-attaching member is connected to the case, as described, the completed structure, so far as the case is con- 110

cerned, is then subjected to the usual water-proof coating.

By wrapping the string under the rail-attaching member, or around it, as previously shown and described, and then across the top of the case, as shown, the rail-attaching member is tightly drawn to the under side of the case, as will be readily understood, and this manner of applying the string to the case and the strap has not, so far as I am aware, been heretofore done.

I do not limit myself to the X-shaped arrangement of the string where it crosses the side of the case, although this is the preferred arrangement, for I find that the string may be passed across the top of the case in parallel arrangement instead of X-shaped arrangement.

The term "string" as used in the claims includes a fiber string, or a string of properly sized annealed metal.

The improvement has a particular adaptability for attaching a spring-rail-attaching member to a fiber case. In all the figures of the drawing, the case is made of fiber and so is the embracing and clamping ring.

With the means heretofore used for attaching the spring rail-engaging members to fiber cases, it has been necessary to use a metal clip of some sort. By the use of the string applied in the manner described, I am able to secure a spring rail-attaching member to a fiber case in an efficient manner without the use of a metal clip. Where a metal clip is used, it is liable to fly, when the torpedo is exploded. The spring, however, which is attached to the rail does not fly, and by using a fiber string there is nothing to fly when the torpedo is exploded by the wheels of a locomotive or car.

Having thus described my invention, what I claim and desire to secure by Letters Patent is:

1. The combination with a case of a railway signal torpedo and rail-attaching member at one side thereof, of a string passed under the rail-attaching member at points

adjacent the edge of the case and across the opposite side of the case, and a clamping member for holding the string in its wrapped 50 position.

2. The combination with a railway signal torpedo case, of a rail-attaching member located at one side thereof, a string passed under the rail-attaching member at points 55 located at the edge of the case and across the opposite side of the case in X-shape arrangement, and a clamping member for holding the string in its wrapped position.

3. The combination with a case of a rail-way signal torpedo, of a rail-attaching member applied to one side thereof, a string extending across the opposite side of the case down the edge of the case and under the rail-engaging member at the edge of the case, 65 and a clamping ring embracing the edge of the case and the string, clamping the string between the ring and the edge of the case.

4. The combination with a case of a rail-way signal torpedo, of a rail-engaging strap applied to one side thereof, a string extending across the opposite side of the case in X-shaped arrangement, down the edge of the case and under the rail-engaging member, and a ring embracing the edge of the case 75 and a string between it and the case.

5. The combination with a railway signal torpedo having a fiber case, of a spring metal rail-attaching member applied to one side of the case, a fiber string extending across 80 the other side of the case down its edges and under the spring at the edge of the case, and means attaching the string to the case.

6. The combination of a railway signal torpedo having a fiber case, of a metal spring 85 rail-attaching member applied to one side of the case, a fiber string extending across the opposite side of the case and under the spring at the edge of the case, and a fiber ring embracing the string between it and the 90 edge of the case.

In testimony whereof I hereunto affix my signature.

FRANK DUTCHER.
